UNITED STATES PATENT OFFICE

LOYD SCRUGGS, OF UNIVERSITY CITY, MISSOURI

STOVE LID

Application filed February 5, 1927. Serial No. 166,174.

This invention relates to stove lids such as are used on stoves for protecting cooking utensils or other objects from the direct action of the fire.

In order that the lids of a stove may be rearranged or removed easily when they are in a heated condition, it is the universal custom to construct them in such a manner that a device, generally referred to as a lid lifter, can be easily engaged with a lid so as to form a handle on the lid by means of which the lid can be raised, removed or shifted into a different position and the handle thereafter easily disconnected from the lid. Notwithstanding the fact that most of the elements which make up a stove have been improved greatly in efficiency, appearance and ease of handling, the conventional stove lid that is now in general use is of the same construction as the lids that were first used on stoves and is provided in its top face with an undercut pocket of considerably greater width than depth, that is adapted to receive a relatively shallow, angularly-disposed portion on the lifter of approximately the same width as the pocket in the lid, whose side edges are rounded off so as to permit said portion to be easily withdrawn from the pocket or introduced into same so that the end of said portion can be quickly engaged with the undercut part of the pocket in the lid. In handling a stove lid of the construction above described the lifter can be manipulated so as to tilt the front edge of the lid upwardly or downwardly without liability of the lid becoming disconnected from the lifter, but if the user twists or turns the lifter in such a way as to tilt the lid laterally into an inclined position, the lid will slide off the lifter, due to the fact that the side walls of the pocket in the lid and the opposed side edges of the broad, shallow portion of the lifter that projects into the pocket are not of sufficient area to effectively resist the torsional strain, tending to turn the lid relatively to the lifter and make it roll off of the lid engaging portion of the lifter.

The object of my invention is to provide a stove lid that is equipped with an under-

cut lid lifter pocket which is of such shape or form that when the lifter is arranged in operative engagement with the lid, the user can tilt the front edge of the lid upwardly or downwardly and can also tilt the lid laterally into an inclined position, or even into a vertical position, without liability of the lid turning relatively to the lifter and rolling off of the portion of the lifter that is positioned in the pocket in the lid.

To this end I have devised a stove lid that is equipped with an undercut lifter pocket that is of greater depth than width and which is provided with side walls which have sufficient bearing area on the portion of the lifter that is positioned in said pocket to eliminate the possibility of the lid turning or rotating relatively to the lifter when the lifter is twisted or turned to tilt the lid laterally into an upright or substantially upright position. The lifter pocket is preferably of greater length than width and the side walls of said pocket are preferably arranged in parallel relation and disposed at substantially right angles to the top face of the lid, the undercut part of the pocket being formed by a portion of the top surface of the lid that overhangs one end of said pocket.

The lifter that I prefer to use with my improved stove lid is provided with a terminal portion of approximately the same thickness as the width of the pocket in the lid and of sufficient depth and length to provide parallel bearing surfaces on the sides of said portion of relatively great area, that cooperate with the side walls of the pocket in the lid to effectively resist the torsional strain or twisting strain exerted on the lid, due to the force of gravity, when the lifter is twisted to tilt the lid sidewise into an upright position. Projecting forwardly from said terminal portion is a projection that is adapted to project under and engage the underside of a portion of the lid that overhangs said pocket, and at or adjacent the rear side of the terminal portion of the lifter is a means that engages the top side of the lid when the terminal portion of the lifter is in

operative engagement with the overhanging wall of the pocket in the lid, said means constituting a stop or abutment on the lifter that limits the rocking movement of 5 the lifter relatively to the lid in one direction.

Figure 1 of the drawings is a top plan view of a stove lid and lifter embodying my invention, with the shank of the lifter 10 broken away.

Figure 2 is a side elevational view of said lid and lifter.

Figure 3 is an enlarged side elevational view of a portion of the lifter detached from 15 the lid.

Figure 4 is an enlarged top plan view of a portion of the lid, with the lifter removed.

Figure 5 is a vertical sectional view, taken on the line 5—5 of Figure 4, with the lifter 20 shown in broken lines.

Figure 6 is a bottom plan view of a portion of the lid.

Figure 7 is a side elevational view, illustrating another way that the lifter can be 25 constructed; and

Figure 8 is a perspective view, illustrating how the lid can be tilted laterally into an upright position without liability of becoming detached from the lifter.

Referring to the drawings which illustrate the preferred form of my invention, A designates a stove lid which consists of a flat, disk-shaped metal member that is provided in its top face with a pocket 1 formed by 35 integral portions of the lid, and adapted to receive a portion on a lid lifter B that constitutes a detachable or removable handle for the lid. The pocket 1 is of greater depth than width and is preferably made longer 40 or of greater length than the width of said pocket, and at one end of said pocket is an undercut part formed preferably by an integral portion α of the top surface of the lid that overhangs one end of the pocket 1. The side walls 2 of the pocket 1 are formed by 45 integral portions of the lid, whose opposed faces are straight or parallel relation and preferably disposed at right angles to the top surface of the lid, thus forming a relatively long, deep and narrow pocket in the lid, whose inner end extends under an integral portion α of the lid that constitutes part 50 of the top surface of the lid.

The lifter B is provided at its lower end 55 with a flat terminal portion of the same width as the pocket in the lid, whose side faces are straight or parallel and are adapted to bear against the opposed inner surfaces of the side walls of said pocket. Projecting 60 forwardly from said terminal portion is a flat projection 3, of the same thickness as said terminal portion, that is adapted to project under and bear against the underside of the portion α of the lid which overhangs 65 one end of the pocket in the lid. When the

lifter is arranged in operative engagement with the lid, as shown in broken lines in Figure 5, or in full lines in Figure 8, the side faces of the flat terminal portion of the lifter co-operate with the side walls 2 of the 70 pocket in the lid, and the projection 3 on

said terminal portion co-operates with the part α of the lid to effectively resist torsional strains tending to make the lid turn and roll 75 off of the lid engaging portion of the lifter when the lifter is twisted to tilt the lid laterally into an upright position, as shown in Figure 8, the terminal portion of the lifter being of greater length and depth than the width of the pocket in the lid, so that when 80

the lifter is arranged in operative engagement with the lid, the side faces of the terminal portion of the lifter will have a bearing surface on the side walls of the pocket of sufficient area to enable the lid to be tilted 85

upwardly, downwardly or sidewise without liability of the lid becoming disengaged from the lifter. At or adjacent the rear end of the terminal portion of the lifter is a means that is adapted to co-operate with the top surface of the lid to limit the downward 90

rocking movement of the lifter relatively to the lid, and thus cause the top edge of the projection 3 on the terminal portion of the lifter to press upwardly against the underside of the overhanging wall α of the pocket 1 in the lid when the lifter B is arranged 95

in operative position, as shown in Figure 2, said means either consisting of a shoulder or abutment member 4 on the lifter that lies in the same vertical plane as the terminal portion of the lifter, or lugs 5 that project laterally from the opposite sides of the terminal portion of the lifter, as shown in Figure 7, and which are adapted to bear against 100

the top surface of the lid when the lifter is arranged in operative position. The lifter can be provided with any suitable kind of a handle 6, either a handle of skeleton-like construction formed from a piece of coiled 105

wire, or a handle formed integral with the shank of the lifter.

While I prefer to provide a lifter of the construction above described for handling or manipulating the lid, I wish it to be 115 understood that my improved lid is not limited to use with such a lifter, for one desirable feature of my lid is that it can be

lifted from the stove or shifted into a different position on the stove with any kind of a device provided with a straight sided portion of slightly less width than the pocket 1 in the lid that can be inserted in said pocket with the end of said portion positioned under the overhanging wall α of the 120

pocket, the length and depth of the side walls 2 of the pocket being great enough to effectively resist torsional strains on the lid tending to make it roll off of the device. A 125

stove lid of the construction above described 130

is a decided improvement on the conventional stove lid now in general use, in that it overcomes the necessity of the operator using considerable care and skill when 5 handling the lid, in order to maintain the lid in engagement with the lifter; it can be manufactured as cheaply as the conventional stove lid; it has a lid lifter pocket that is less liable to become filled with dirt or food 10 which boils over from the cooking utensil under which the lid is arranged, and still another desirable feature of my improved stove lid is that it can be used in conjunction with a stove lifter that can be stamped out 15 of a flat bar or other flat piece of metal of substantially the same thickness as the width of the pocket 1 in the lid when the lifter is constructed in the manner illustrated in Figure 3.

20 Having thus described my invention, what I claim as new and desire to secure by Letters Patent is:

1. A stove lid provided with an unobstructed lifter pocket of considerably less 25 width than depth, having straight, parallel side walls formed by integral portions of the lid, and an integral portion on the lid constituting part of the top face of the lid, disposed so as to overhang one end of said 30 pocket.

2. A stove lid provided in its top face with an elongated slot whose length is considerably greater than its width, and integral portions on the underside of the lid which 35 form an unobstructed lifter pocket of considerably greater depth than its width, having parallel side walls that merge into the side edges of said slot and form continuations of same and which extend underneath 40 a portion of the top surface of the lid that forms an overhanging top wall for the inner end of said pocket.

3. In combination, a stove lid and lifter 45 detachably combined; said lid provided with an unobstructed lifter pocket of less width than depth and of considerably greater length than width and having straight, parallel side walls formed by integral portions of the lid, an integral portion on the 50 lid constituting part of the top face thereof and disposed to overhang the inner end of said pocket; and said lifter being provided with a terminal portion having straight and parallel sides and of substantially the same 55 width and length as said pocket, said terminal portion being thereby adapted to fit snugly into said pocket and extend beneath said integral portion of the lid overhanging the inner end of said pocket.

60 4. In combination, a stove lid and lifter 65 detachably combined; said lid provided with an unobstructed lifter pocket of less width than depth and of considerably greater length than width and having straight, parallel side walls formed by integral por-

tions of the lid, an integral portion on the lid constituting part of the top face thereof and disposed to overhang the inner end of said pocket; said lifter being provided with a terminal portion having straight and 70 parallel sides and of substantially the same width and length as said pocket, said terminal portion being thereby adapted to fit snugly into said pocket and extend beneath said integral portion of the lid overhanging 75 the inner end of said pocket, and means on said terminal portion adapted to bear against the top face of said lid adjacent the outer end of said pocket when the lifter is in operative engagement with the lid.
